Primary Examiner—Wallace R. Burke*Assistant Examiner*—Freda S. Nunn*Attorney, Agent, or Firm*—Dykema Gossett**[57] CLAIM**

The ornamental design for a computer programming terminal, as shown and described.

DESCRIPTION

FIG. 1 is a top and front perspective view of a computer programming terminal with the keyboard in an extended position showing my new design;

FIG. 2 is a right side elevational view thereof;

FIG. 3 is a left side elevational view thereof;

FIG. 4 is a bottom plan view thereof;

FIG. 5 is a back elevational view thereof;

FIG. 6 is a right side elevational view thereof with the keyboard shown in the stored position;

FIG. 7 is a left side elevational view thereof;

FIG. 8 is a bottom plan view thereof; and,

FIG. 9 is a top, front and left side perspective view thereof.
